UNITED STATES PATENT OFFICE.

SKILES F. MASSY, OF PITTSBURGH, PENNSYLVANIA.

SANITARY CUSPIDOR.

Application filed September 22, 1925. Serial No. 57,884.

To all whom it may concern:

Be it known that I, SKILES F. MASSY, a citizen of the United States, residing at Pittsburgh, in the county of Allegheny and State of Pennsylvania, have invented certain new and useful Improvements in a Sanitary Cuspidor, of which the following is a specification.

This invention relates to an improved sanitary cuspidor of the type embodying a bowl, a removable receptacle in said bowl, and a funnel or mouth for directing material into the receptacle.

My principal aim is to generally improve upon structures of this type by providing one wherein the upper portion of the bowl is inclined inwardly and upwardly to form a restricted opening, through and beyond which the removable receptacle extends, whereby to permit the extending portion to be grasped by the hand when necessary to remove the receptacle, and without soiling the hands.

Another feature is to provide the top portion of the bowl with an upstanding flange which is spaced from the restricted opening, and which constitutes a means for carrying connecting pins which are engaged with bayonet slots formed in a collar which depends from the central portion of the funnel shaped mouth and is telescopically connected with said flange.

An equally important structural feature of the invention is the provision of a spring 35 clamping device which is carried by said collar and is fashioned to engage the upwardly extending portion of the receptacle to maintain the latter firmly in place.

40 Other features and advantages of the invention will become apparent during the following description and drawing.

In the accompanying drawing forming a part of this application and in which like numerals are employed to designate like parts throughout the same:

Figure 1 is a side elevation of a cuspidor constructed in accordance with the present invention.

50 Figure 2 is a central vertical section through the same showing the details and relative arrangement more plainly.

Figure 3 is a horizontal section taken approximately upon the plane of the line 3-3 of Figure 1 looking downwardly.

Referring to the drawing in detail the

reference character 1 designates what may be conveniently referred to as bowl. The general external configuration of this bowl may be of any desirable formation. The top portion of the bowl inclines inwardly and upwardly as at 2, and forms a restricted opening at the top. Mounted on this portion 2 is an upstanding flange 3. This flange is spaced from the edge of the opening, and is provided with outstanding pins 4 engaged with the bayonet slots formed at diametrically opposite points in a depending collar 5 on a funnel shaped mouth 6. It will be noted that the collar is relatively deep, and is telescopically connected with the upstanding flange 3. Moreover it depends from the intermediate portion of the funnel 6 and this allows the inner portion of the funnel to project down into the mouth of the removable collecting receptacle 7. This receptacle is of wax paper or other suitable material, and extends through the restricted opening in the bowl and outwardly beyond the flange 3 and tightly contacts the under side of the funnel shaped mouth as indicated plainly in Figure 2. While considering Figure 2, I wish to direct attention to the fact that the funnel shaped mouth 6 is of a diameter greater than the bowl, and it therefore extends outwardly beyond the bowl and overhangs it a distance sufficient to reduce the possibility of dirt accumulating on the surface of the bowl. Obviously, this large mouth serves as an effective means for directing the dirt into the receptacle.

As before intimated, a novel supplemental retaining device in the form of a clamp 8 is employed for maintaining the removable receptacle 7 in place. The construction of this device is shown better in Figure 3, and by referring to this figure it will be seen that it comprises a resilient wire member comprising a ring-like receptacle encircling part having its intermediate portion 9 connected with the aforesaid collar 5. The free end portions of the rings are disposed in crossed relation and formed with finger grips 10. These finger grips extend through elongated slots 11 formed in the front of the collar. The natural tendency of the opposed portions of the ring is to resiliently grip the mouth of the receptacle. In this connection and by directing attention to Figure 2 it will be noted that the upper end

portion 12 of the aforesaid receptacle 7 bears against the under side of the funnel shaped mouth 6. Moreover, the clamp is disposed on a plane so that the side portions of the ring engage this part 12 of the receptacle. This prevents crushing of the receptacle as the funnel then acts as a backing member therefor.

It is obvious that it is necessary to rotate 10 the parts 5 and 6, as a unit, with respect to the bowl 1, in order to disconnect them. The connection however is in the form of a common bayonet slot and pin connection which is not deemed to be new. It is believed however that it is a feature of importance to have the funnel shaped mouth overhang the bowl and upper portions thereof as shown, to prevent undue accumulation 15 of dirt on the exterior of the bowl. It is obvious that the accumulation of dirt in this manner would be objectionable because it is necessary to grasp the parts and rotate them with respect to each other in order to disconnect them. It is also thought to be 20 advantageous to have the upper portion of the receptacle extend above the restricted opening in the top of the bowl, and to contact the under side of the funnel shaped mouth so that the material is effectively directed into the receptacle. In fact, the presence of the clamp is deemed to be an important feature in that it holds the receptacle firmly in place even if the cuspidor is accidentally overturned.

It is believed that by considering the description in connection with the drawings persons familiar with devices of this class will be able to obtain a clear understanding 35 of the invention. Therefore, a more lengthy description is thought to be unnecessary.

While the preferred embodiment of the invention has been shown and described, it is to be understood that minor changes coming within the field of invention claimed 40 may be resorted to if desired.

A particular feature of importance is the employment of the clamp in that it maintains the paper receptacle in engagement with the inner end portion of the funnel shaped mouth so that the latter and receptacle may be removed as a unit from the bowl, without touching the receptacle, after which the clamp may be released to permit the receptacle to be discharged into a suitable place of deposit.

Having thus described the invention, what I claim as new is:—

1. A sanitary cuspidor comprising a bowl having its upper end directed inwardly and terminating in a restricted opening, a vertical flange extending from said upper end

and surrounding said opening and being spaced from the peripheral edge thereof, a receptacle removably fitted into said bowl and extending through and beyond the restricted opening, the upper portion of the receptacle extending above said flange and the edge of said opening being in contact with the wall of the receptacle, a funnel shaped mouth having its lower end telescoping into the upper end of the receptacle and flaring outwardly beyond said upper end, and the body portion of the bowl, a collar depending from the intermediate portion of said mouth and telescopically engaged with said flange, and coacting means between the flange and collar for detachably connecting the collar with the flange.

2. A sanitary cuspidor comprising a bowl having its upper end directed inwardly and terminating in a restricted opening, a vertical flange extending from said upper end and surrounding said opening and being spaced from the peripheral edge thereof, a receptacle removably fitted into said bowl and extending through and beyond the restricted opening, the upper portion of the receptacle extending above said flange and the edge of said opening contacting the wall of the receptacle, a funnel shaped mouth having its lower end telescoping into the upper end of the receptacle and flaring outwardly beyond said upper end, and the body portion of the bowl, a collar depending from the intermediate portion of said mouth and telescopically engaged with said flange, and coacting means between the flange and collar for detachably connecting the collar with the flange, and means carried by said collar and engaged with the upper extended portion of said receptacle for maintaining the latter in place.

3. A sanitary cuspidor comprising a bowl having an opening in its top, a flange surrounding said opening and connected with said top, a funnel shaped mouth, a collar connected to the intermediate portion of said mouth and depending therefrom and telescopically connected with said flange, a receptacle in said bowl extending through the opening in the top thereof and having its upper end in contact with the inner end portion of said mouth, and a resilient clamping device carried by said collar and having a ring like portion surrounding the top of the receptacle and holding it firmly against said mouth so that the latter and receptacle may be removed from the bowl as a unit.

In testimony whereof I affix my signature.

SKILES F. MASSY.
